HANDLE CONSTRUCTION

Filed Aug. 5, 1926

UNITED STATES PATENT OFFICE

LE ROY C. SCHENCK, OF EAST MOLINE, ILLINOIS, ASSIGNOR, BY MESNE ASSIGNMENTS, TO TROY LAUNDRY MACHINERY COMPANY, INC., OF DOVER, DELAWARE, A CORPORATION OF DELAWARE

HANDLE CONSTRUCTION

Application filed August 5, 1926. Serial No. 127,261.

The present invention relates to handle construction.

More particularly the present invention relates to handle construction such as is used in washing machine cylinders. In controlling the sliding doors of washing machine cylinders it is convenient to use the latches on such doors as operating handles. The handles of such latches should be so arranged that when the latches are performing latching functions, said handles should occupy unobtrusive positions, and at other times such handles should protrude to a sufficient extent to be easily grasped.

An object of the present invention is to provide handle construction suitable for washing machine cylinders which will remain in either unobtrusive or projecting position, depending upon the position in which they are placed, which handle construction involves a minimum of parts.

A further object is to provide a handle construction which when performing latching functions will occupy a minimum of space radially of the washing machine cylinder and which handle construction is simple to manufacture and easy to assemble.

A further object is to provide a handle construction well adapted to meet the needs of commercial operation, which handle construction will be light in weight, effective in operation and cheap to construct and assemble.

Further objects will appear as the description proceeds.

Referring to the drawings—

Figure 1 is a view in elevation of part of a washing machine cylinder having one embodiment of the present invention applied thereto;

Figure 2 is a view on an enlarged scale of part of the structure shown in Figure 1, said Figure 2 disclosing the details of the latching mechanism;

Figure 3 is a sectional view taken along the plane indicated by the arrows 3—3 of Figure 2;

Figure 4 is a view similar to Figure 3, but showing the latching bolt retained in unlatching position; and

Figure 5 is a perspective view illustrating the latch shown in the preceding figures.

Referring first to Figure 1, the numeral 10 indicates a washing machine cylinder (only one end thereof being shown) which cylinder is provided with trunnions, one of which is indicated by the numeral 11, whereby said cylinder may be rotatably supported within an enclosing casing (not shown).

Said cylinder 10 is provided with a plurality of doors 12—12 mounted to slide circumferentially thereof, guideways 13—13 being provided for guiding said doors 12 in their sliding movements. Each of the doors 12 is provided, adjacent to its closure edge, with a depressed portion indicated by the numeral 14. Said depressed portion serves the double function of strengthening the door along its edge and of providing a recess for latches 15—15, two of which are provided on each sliding door. The cylinder 10 is provided with end walls and partitions, which are not shown in detail but which provide socket portions 16 for cooperation with the latches 15 above referred to.

Each of the latches 15 comprises a housing 17 having ear portions 18—18 by means of which said housing may be bolted or otherwise secured to the material of the door 12. Mounted for reciprocating movement within the housing 17 is the bolt 19 adapted to project through the aperture 20 in the end wall of the depressed portion 14 of the door 12. Said bolt 19 when in registry with the adjacent socket portion 16 is adapted to enter said socket portion 16 to hold the door in closed position.

The bolt 19 in a preferred embodiment takes the form of a frame having the two side walls 20'—20' providing between them the recess 21. Disposed within the recess 21 is the coil spring 22, one end of which is adapted to fit over a lug 23 projecting forwardly from the rear wall of the housing 17. The other end of the spring 22 is adapted to fit over the stud 24, which projects rearwardly from the forward portion of the bolt 19.

The numeral 25 indicates a handle having the manually operable portion 26 and the two leg portions 27—27 adapted to straddle the

coil spring 22. Said leg portions 27-27 are provided with pintles 28-28, which pintles have bearing engagement in the cylindrical apertures 29-29 in the side walls 20'-20' of the bolt 19. The handle 25 lies within the aperture 30 in the upper wall of the housing 17. As will appear from an inspection of Figures 3 and 4 of the drawings, the planes bounding the upper side of the handle 25 and the forward sides of the leg portions 27-27 are substantially at right angles to one another. Accordingly, when the handle 25 is moved to the position shown in Figure 3, the legs 27-27 will be pivoted about the edge 31 defining the forward boundary of the opening 30. Said forward sides of the leg portions 27-27 are notched as indicated by the numerals 31^a-31^a to receive said edge 31. The spring 22, reacting between the housing 17 and the bolt 19, will have the effect of tending to urge the handle 25 forwardly with the notches 31^a-31^a receiving the edge 31 and also tending to urge said handle in a clockwise direction and holding said handle in a non-protruding latching position. When the operative desires to raise the handle 25 to a protruding position, as indicated in Figure 4, he will pull said handle rearwardly, i. e. in the direction of the arrow in Figure 3 to free the notched portion of said handle from the edge 31 and will swing said handle about said edge as an axis. The pintles 28-28 will force the bolt 19 rearwardly against the tension of the spring 22, and the upper portion of the handle 25 will engage the edge 31. The effect of the spring 22 will be to hold the handle 25 in the position indicated in Figure 4, in which position the bolt 19 is retracted and the handle 25 is in protruding position, whereby said handle may be readily grasped by the operator for manipulating the corresponding door 12.

Mounted within the bolt 19 is the plunger 32, spring pressed forwardly by means of the spring 33, which spring 33 is held in position by means of the set-screw 34, operable from the rear extremity of the bolt 19. Said plunger 32 is adapted to engage one of the leg portions 27 of the handle 25. When the handle 25 is in the position shown in Figure 4, the spring 33 will act cumulatively with the spring 22 to hold the handle 25 in protruding position. When the handle 25 is moved in non-protruding position, as shown in Figures 2 and 3, said spring 33 will also have a cumulative effect with the spring 22 to hold said handle 25 in non-protruding position. By reason of the spring 33 the handle 25 will be safely held against retraction from locking engagement with the edge 31 and against outward movement under forces encountered in service, even though the spring 22 is in substantially uncompressed condition. By reason of the provision of the spring 33, the spring 22 may be made relatively light in

weight, thereby reducing cost and reducing the amount of force which an operator must exert in moving the handle 25 from the position shown in Figure 3 to that shown in Figure 4, or reversely.

Though a preferred embodiment of the present invention has been described in detail, it will be clear that many modifications will occur to those skilled in the art. It is intended to cover all such modifications that fall within the scope of the appended claims.

What is claimed is-

1. In an article of the class described, a housing, a bolt mounted for reciprocating movement within said housing and an operating member for said bolt having pivotal connection with said bolt, a spring disposed in position to exert pressure between said housing and said bolt to hold said bolt in projected position, said operating member being adapted to have a swinging movement and having a pair of surfaces disposed in angular relation with one another which surfaces are connected by means of a smoothly rounded surface, all said surfaces being adapted to abut against one portion of said housing bounding said aperture, said operating member and said housing having shouldered engagement with one another when said bolt is in projected position to prevent said operating member from swinging until said operating member has been moved in the line of action of said spring to disengage said shouldered engagement.

2. In an article of the class described, a housing, a locking bolt within said housing and a swinging handle having pivotal connection with said bolt, said handle comprising an elongated operating portion adapted to be disposed alternatively in parallel relationship with the line of movement of said bolt and in substantially right angular relationship with said line of movement, said handle having another portion in substantially right angular relationship with the elongated portion thereof, a spring reacting between said housing and said bolt to alternatively hold either said elongated portion or said other portion of said handle in engagement with said housing, said handle and said housing having shouldered engagement with one another when said bolt is in projected position to prevent said handle from swinging until said handle has been moved in the line of action of said spring to disengage said shouldered engagement.

3. In an article of the class described, a housing, a locking bolt within said housing and a swinging handle having pivotal connection with said bolt, said handle comprising an elongated operating portion adapted to be disposed alternatively in parallel relationship with the line of movement of said bolt and in substantially right angular relationship with said line of movement, said handle

having another portion in substantially right angular relationship with the elongated portion thereof, a spring reacting between said housing and said bolt to yieldably hold either 5 said elongated portion or said other portion of said handle in engagement with said housing, and a supplementary spring positioned to react between said bolt and said handle to supplement the effect of such first mentioned 10 spring, said handle and said housing having shouldered engagement with one another when said bolt is in projected position to prevent said handle from swinging until said handle has been moved in the line of action of 15 said spring to disengage said shouldered engagement.

4. In combination, a housing, a reciprocable bolt within said housing, a handle for moving said bolt, said handle being adapted 20 to engage said housing with a pivoting movement about an axis which changes relative to said handle as said handle is swung, said handle being pivotally connected to said bolt about an axis which is fixed relative to said 25 bolt, a spring positioned to react between said housing and said bolt, said handle being provided with surfaces in angular relationship with one another adapted to engage said housing in alternative positions, in cooperation 30 with said spring, to yieldably hold said bolt in either retracted or projected position, said handle and said housing having shouldered engagement with one another when said bolt is in projected position to prevent said handle 35 from swinging until said handle has been moved in the line of action of said spring to disengage said shouldered engagement.

5. In combination, a housing, a reciprocable bolt within said housing, a handle pivoted 40 to said bolt for moving said bolt, said handle being adapted to engage said housing with a pivoting movement about an axis which changes relative to said handle as said handle is swung, said handle being connected to said bolt about an axis which is fixed relative to said bolt, said handle being provided with surfaces in angular relationship with one another adapted to engage said housing in alternative positions, in cooperation 45 with said spring, to yieldably hold said bolt in either retracted or projected position and a supplementary spring reacting between 50 said bolt and said handle.

6. In an article of the class described, a 55 housing, a bolt within said housing and a swinging handle having pivotal connection with said bolt, said handle comprising an elongated operating portion adapted to be disposed alternatively in parallel relationship 60 with the line of movement of said bolt and in substantially right angular relationship with said line of movement, said handle having another portion in substantially right angular relationship with the elongated portion 65 thereof, a spring reacting between said

housing and said bolt to yieldably hold either 70 said elongated portion or said other portion of said handle in engagement with said housing, and a supplementary spring positioned to react between said bolt and said handle to supplement the effect of such first mentioned 75 spring, said other portion having shouldered engagement with said housing when said elongated portion is in parallel relationship with said line of movement to prevent said handle from swinging until said handle has been moved in the line of action of said spring to disengage said shouldered engagement.

7. In combination, a housing, a reciprocable bolt within said housing, a handle pivoted to said bolt for moving said bolt, a spring, said handle being adapted to engage said housing with a pivoting movement about an axis which changes relative to said handle as said handle is swung, said handle being connected to said bolt about an axis which is fixed relative to said bolt, said handle being provided with surfaces in angular relationship with one another adapted to engage 80 said housing in alternative positions, in cooperation with said spring, one of which positions is a locking position, to yieldably hold said bolt in either retracted or projected position and a supplementary spring reacting between 85 said bolt and said handle, one of said surfaces having shouldered abutment means engaging said housing when said bolt is in said locking position to prevent said handle from swinging until said handle has been 90 moved in the line of action of said spring to disengage said shouldered engagement.

8. In combination, a housing, a reciprocable bolt within said housing, a handle for moving said bolt, said handle being adapted 105 to engage said housing with a pivoting movement about an axis which changes relative to said handle as said handle is swung, said handle being pivotally connected to said bolt about an axis which is fixed relative to said bolt, a spring positioned to react between said 110 housing and said bolt, said handle being provided with surfaces in angular relationship with one another adapted to engage said housing in alternative positions, in cooperation with said spring, to yieldably hold said bolt in either retracted or projected position, 115 said handle and said housing having a tongue and groove engagement with one another when said bolt is in projected position, whereby said handle may not swing until said handle has been moved in the line of action of said spring to disengage said tongue and groove connection.

Signed at East Moline, Illinois, this 2nd 125 day of August, 1926.
